(57) **CLAIM**

The ornamental design for a cover plate for wall mounting electrical apparatus, as shown and described.

DESCRIPTION

FIG. 1 is a bottom view of a cover plate for wall mounting electrical apparatus showing my new design;

FIG. 2 is a right side view thereof;

FIG. 3 is a front view thereof;

FIG. 4 is a left side view thereof;

FIG. 5 is a top view thereof; and,

FIG. 6 is a perspective view thereof.

The rear view has not been shown as it is not being claimed.
